SEWER CLEANING APPARATUS

John O. Magruder, Los Angeles, Calif., assignor of
one-half to George H. Werfelman, Los Angeles,
Calif.

Application July 24, 1935, Serial No. 32,887

10 Claims.

(Cl. 242—90)

This invention relates to improvements in apparatus for clearing sewer-pipe of stoppages or cleaning the interior of any pipe without dismantling the same.

5 The principal object of my invention is to provide a machine of simple and practicable construction including a reel-wheel upon which a wire of considerable length is wound and which is mounted for rotation on its axis to pay out and 10 retract the wire and which is mounted in a frame whose independent axis of rotation is in alignment with the length of wire extending into the sewer-pipe and at right angles to the axis of rotation of said wheel, together with 15 means to rotate said wheel in either direction and said frame either in unison or simultaneously with the reel-wheel or the frame separately to rotate said wire in the sewer-pipe to cause a suitable tool at its extremity to whip 20 about therein to dislodge the stoppage plug in the pipe and to concurrently advance or withdraw the wire and connected tool.

A further object of my invention is the provision of means to actuate the frame to turn 25 about upon its axis at a constant speed and at a relatively rapid rate whereby the wire paid out is caused to rotate to effectively energize the tool at the end thereof to dislodge the stoppage matter in the pipe and to simultaneously rotate 30 the reel through novel variable speed devices in combination with differential apparatus driving the reel from the movement of the frame whereby the reel may be actuated at predetermined relative speeds with respect to the rotation of 35 the frame and in either of its rotary directions.

A still further object of the invention is to provide means to retain the wire upon the reel in a compact coil unaffected by the centrifugal effect produced by the relatively rapid whirling 40 of the frame and reel mounted thereon, said means comprising suitable spring-clips to retain the wire and spring-clamps acting upon the wire to clutch the same close to the rim of the reel and openable in the rotative movements of the 45 reel to admit of the wire entering or leaving the clips.

Other objects and advantages residing in my invention, and objects relating to details of construction and various arrangements and adaptations of parts thereof, will be fully set forth in 50 the course of the detailed description to follow.

The accompanying drawings illustrate by way of example a representative form of my invention, in which:

Figure 1 is a plan view of apparatus embodying my invention, partly broken away.

Fig. 2 is a view in side elevation of the same.

Fig. 3 is a view in front elevation of the machine showing in detail and on an enlarged 5 scale the driving and controlling devices thereof.

Fig. 4 is a view in side elevation of the variable speed control-lever, as shown in Fig. 3.

Fig. 5 is a view in cross-section of the rotative frame and associated parts.

Fig. 6 is a plan view of the driving-pulley 10 assembly illustrating the variable-speed devices employed.

Fig. 7 is a detail view in side elevation of a 15 spring-clip element of the invention taken transversely of the wire-reel.

Fig. 8 is a detail view in side elevation of a 20 spring-clamp element of the invention, shown in broken lines in open condition.

Referring to said views, the reference numeral 20 10 indicates the lower horizontal structural elements of a carriage supported upon casters, such as 11, and 12 designates the upper horizontal elements thereof, connected by suitable frame-work 13 to form a relatively light and rigid mobile 25 support for the apparatus to be described. A frame comprising the longitudinal side-bars 15 and end-bars 16, is mounted to rotate on its major axis longitudinally of the carriage, the 30 end-bars 16 being provided with trunnions 17 and 18 rigid therewith and respectively rotatable in anti-friction bearings 20 and 21 mounted upon the horizontal elements 12 of the carriage. A 35 grooved pulley-wheel 22 is keyed at 23 to the trunnion 17 and is operatively connected by a belt 25 with a pulley-wheel 26 secured to a motor-shaft 27 actuated by a motor 28 seated on the lower horizontal structure 10 of the carriage whereby the frame is rotated at a considerable 40 speed about its longitudinal axis.

A shaft 30 is mounted transversely of the frame to rotate in bearings 31 and 32 rigidly connected to the side-bars 15. A reel-wheel 33 45 consisting of a hub 35, spokes 36 and a circular peripheral rim 37 is keyed to said shaft and is arranged to be rotated thereon through a bevel-gear 38 keyed to said shaft and driven through a bevel-pinion 40 in a manner to be presently described. Spring-clips 41 are secured to the rim 37 at spaced intervals to receive and reliably retain the wire 42 and intermediate said clips 50 spring-pressed clamps 43 are provided to engage and press the wire into close engagement with the rim. Said wire is desirably formed in one 55

continuous length and is secured at one end to said rim by taping or clamping, or other convenient method and its opposite end extends through a tube 45 fixedly secured to a transverse member 46 of the frame and thence extends through a hollow-shaft 47 journaled axially in the tubular trunnion 17 and is thus led from the machine in the axis of rotation of the frame through a hardened steel tip 48 and at 5 its extremity is formed in or is provided with a suitable tool 50 adapted to the work of dislodging the stoppage matter with which the sewer-pipe may be plugged. Said frame and wheel may be actuated in either direction in 10 their respective modes of rotation so that two tubes 45 are provided uniting in a common outlet 51 while the respective tubes are divergently directed in arcs substantially corresponding oppositely to the radius of the reel-wheel 33. 15

20 It has been stated that the frame is rotated upon its trunnions 17 and 18 which will cause the wire extending through the hollow shaft 47 and the tool 50 to rotate and such action, when the wire and tool are advanced into the sewer-pipe, 25 causes the chief effectiveness of the apparatus in cleaning out the plugged pipe. Together with such rotary movement given to the wire the wire may be advanced or retracted while the rotary movement is effected and such action simultaneous 30 with the rotary movement of the tool is extremely efficacious in removing the stoppage material. Such relative movement of the wire is accomplished through the rotation of the reel 33 upon the shaft 30.

35 The pinion 40 in mesh with the gear 38 is keyed to a shaft 52 mounted for rotation longitudinally of the frame and having keyed thereto at its opposite end a gear-wheel 53 in mesh with a toothed-pinion 55 keyed at 56 on the hollow-shaft 40 47. At the opposite end of said hollow-shaft a grooved pulley 57 is keyed of somewhat smaller diameter than the pulley 22 and is connected by a belt 58 with a variable-speed pulley indicated generally by the numeral 60 keyed to the motor-shaft 27, the belt 58 being provided with a suitable tightening device 61.

45 The variable-speed pulley 60 comprises a fixed member 62 keyed to the shaft 27 and a member 63 splined at 65 on said shaft to open and close 50 its angular groove 66 to receive the belt 58 at extreme positions corresponding to those shown by broken lines 58' and 58'' or at any desired position intermediate thereof, as determined by the location of the movable member 63. Said 55 movable member is controlled by a lever 67 pivoted at 68 and connected to the pulley-member through a yoke 70. The upper end of said lever is provided with a latch-bar 71 engageable with a notched quadrant 72 and controlled by a hand-operated toggle device 73 to secure the lever and consequently the movable pulley-member in set 60 position.

65 The frame may be driven at a constant speed but the pulley 57 and shaft 47 with the pinion 55 are driven at speeds even to or slightly in excess or slightly under the speed of the frame through the selective position of the belt 58 in the pulley 60 whereby such excess speed will cause the pinion 55 to drive the gear-wheel 53 in one direction, to actuate the reel through the bevel-gears 38 and 40, with the effect, for example, of paying out wire upon the reel, while if the shaft 47 is driven under the speed of the trunnion 17 the differential in speed will cause the reel to turn 70 in the opposite direction to draw in the wire.

Thus the two main movements, that of the frame to whirl the reel and wire about its own axis, and that of the reel about its independent axis to pay out or draw in the wire are effected simultaneously and with a minimum of mechanical complication. An intermediate position of the belt 58 may be found wherein the rotation of the shaft 47 and the trunnion 17 are equal whereupon the reel will be stationary on its axis. 5

The trunnion 17 is provided with a brake-drum 10 75 engageable by a brake-band 76 actuated by a lever 77 to check the rotation of the frame at the will of the operator. 15

The spring-clips 41, see Fig. 7, are each formed of spring-metal bows 78 secured at their mid-portion 80 to the outer side of the rim 37 and which are spaced apart at their extremities. Said bows are each slotted adjacent their said extremities wherethrough the contiguous outwardly diverging ends 81 of a looped spring 82 are passed, the medial portion of said spring extending about the rim 37. Thus in the revolutions of the reel to wind the wire thereon the wire will be guided by the respective tube 45 between the ends 81 of the springs 82 to enter the clips where it is retained with the co-operation of the spring-clamps 43 until again withdrawn in the opposite rotation of the reel. The juxtaposition of the spring-ends 81 and the narrow limits afforded in their distension as governed by their interference with the ends of the clip-bows 78 ensures that but the one strand of wire will be released. 20 25 30

Experience has proven that it is difficult to coil wire tightly upon a reel when it is in a state of rapid revolution on an axis transverse to its immediate axis of revolution, as the centrifugal force developed in the wire when being coiled in while subjected to this expanding force causes the coils of wire to seek the outer limits of the spring-clips 41 and even to be thrown out between the spring-ends 81. To avoid this objection I have provided a plurality of spring-clamps 43, see Fig. 8, each comprising a support 83 rigidly mounted on the rim 37 intermediate the spring-clips 41. The clamp-arm 85 is pivotally mounted at 86 on said support and is resiliently pressed toward the rim or against the bunch of wire coiled within the spring-clips by a spring 87. Another arm 88 is surmounted by a channeled roller 90 which is arranged to engage the suitably shaped cam-edge 91 of a plate 92 rigidly mounted in the forward portion of the frame and symmetrically with respect to the major axis thereof to the end that upon the respective clips 41 approaching the tube 45 wherethrough the wire is directed to the hollow shaft 47 the clamp immediately in advance thereof will engage the cam 91 to open the clamp and allow the wire to pay out and upon the clamp passing beyond such cam the clamp will close and retain the wire in bunched condition as described. Thus the clamps are opened in turn as they approach the position where the wire leaves or is wound upon the reel and as the clamps are always closed at all other portions of the periphery of the reel and the wire is retained reliably in close engagement to the rim 37 regardless of the speed of rotation of the frame. It will be further seen that the converse operation will take place in the rotation of the wheel to take in the wire and that the clamps will be opened to allow the wire to enter the clips as it passes through the tubes 45 and will then close to retain it tightly. 55 60 65 70

The operation of my apparatus will be evident from the detailed description given. It should 75

be stated, however, that with the use of my invention lengths of sewer-pipe of over six hundred feet are readily cleaned of all obstructions with the labor of but a single man where heretofore large sections of pipe have been excavated to obtain the same results. The relatively high speed of rotation of the wire and tool 50 whips the tool about in the pipe and tears and hooks into the obstruction of whatever nature and then 10 by alternately advancing and retracting the tool an extremely effective clearing agent is provided.

Having described my invention, what I claim, is:

1. Sewer cleaning apparatus, comprising a carriage, a frame revolvably mounted in said carriage upon trunnions disposed in the longitudinal axis of the frame, one of said trunnions being tubular, a hollow-shaft rotatably borne in said tubular trunnion, a wire-reel rotatably mounted 20 in said frame having its axis of rotation disposed at right angles to the axis of rotation of the frame, operative connections to drive said reel from said shaft, and means to drive said tubular trunnion and said shaft to simultaneously and 25 independently rotate said frame and said reel.

2. Sewer cleaning apparatus, comprising a carriage, a frame revolvably mounted in said carriage upon trunnions disposed in the longitudinal axis of the frame, one of said trunnions being tubular, 30 a hollow-shaft rotatably borne in said tubular trunnion, a wire-reel rotatably mounted in said frame having its axis of rotation disposed at right angles to the axis of rotation of the frame, means to drive said frame through said tubular 35 trunnion at a constant speed, and means to rotate said reel on its said axis of rotation through said shaft at variable speeds in either rotary direction.

3. Sewer cleaning apparatus, comprising a carriage, a frame revolvably mounted in said carriage upon trunnions disposed in the longitudinal axis of the frame, one of said trunnions being tubular, a hollow-shaft rotatably borne in said tubular trunnion, a wire-reel rotatably mounted 45 in said frame having its axis of rotation disposed at right angles to the axis of rotation of the frame, means to drive said frame through said tubular trunnion at a constant speed, and means to rotate said reel on its said axis of rotation 50 through said shaft at variable speeds and in either rotary direction.

4. Sewer cleaning apparatus, comprising a carriage, a frame revolvably mounted in said carriage upon trunnions disposed in the longitudinal axis of the frame, one of said trunnions being tubular, a hollow-shaft rotatably borne in said tubular trunnion, a wire-reel rotatably mounted 55 in said frame having its axis of rotation disposed at right angles to the axis of rotation of the frame, means to direct wire from said reel through said hollow-shaft, means to drive said frame through said tubular trunnion at a constant speed, and means to rotate said reel on its said axis of rotation through said shaft at 60 variable speeds and in either rotary direction.

5. Sewer cleaning apparatus, comprising a carriage, a frame revolvably mounted in said carriage, one of the axes of rotation of the frame being tubular, a shaft rotatably journaled in 65 said tubular axis, a wire-reel rotatably mounted

in said frame having its axis of rotation disposed at right angles to the axis of rotation of the frame, means to rotate said reel on its axis from said shaft, means to drive said frame and said shaft simultaneously and from the same source of power, said means including variable speed devices to effect the rotation of said shaft and reel in either rotary direction and at desired speeds relative to the rotation of the frame.

6. Sewer cleaning apparatus, comprising a carriage, a frame revolvably mounted in said carriage having a tubular trunnion at one end on which it is rotated, a shaft rotatably journaled in said trunnion, a wire-reel rotatably mounted in said frame having its axis of rotation disposed at right angles to the axis of rotation of the frame, a motor, means to actuate said frame from said motor, variable speed devices to actuate said shaft from said motor, a toothed pinion keyed on said shaft, and drive connections between said reel and said pinion including a planetary gear operable by said pinion, and means to actuate said variable speed devices to obtain a differential in the related speeds between said frame and said reel whereby the reel may be actuated in either rotary direction upon its axis.

7. In sewer cleaning apparatus, a reel upon which a coil of wire is wound, means to rotatably actuate said reel, a plurality of spring-clips mounted on the rim of said reel to receive the wire therein, each said clip comprising a pair of relatively rigid bows having their ends spaced apart and slotted adjacent their ends, and a spring having its ends extending through said slots and resiliently closing the space between 35 said bow-ends.

8. In sewer cleaning apparatus, in combination with a reel-wheel, means to rotate said reel, means to receive wire upon said reel, a plurality of spring-pressed clamps mounted on said reel 40 and arranged to press the wire into close relation to the reel-rim, and means to open said clamps at a predetermined point in the rotation of the reel to release a coil of said wire.

9. In sewer cleaning apparatus, in combination with a reel-wheel, means to rotate said reel, a plurality of wire-receiving clips spaced apart on the rim of said reel to receive a coil of wire therein, a plurality of spring-pressed clamps arranged to press the wire into close relation to the rim of 50 the reel, and a cam arranged to be engaged by said clamps at a predetermined point in the revolution of the reel to open said clamps and release the wire.

10. In sewer cleaning apparatus, in combination with a rotatable frame, a reel-wheel mounted for rotation in said frame with its axis of rotation at right angles to the axis of rotation of the frame, a plurality of clips rigidly secured to the rim of said reel to receive the wire wound thereon, a plurality of spring-pressed clamps to press the wire in close proximity to said rim, a tube secured in said frame through which said wire is directed from the reel, and a cam arranged to engage said clamps in the rotation of the reel and to open the same at the point where said wire is drawn from said reel and through said tube.

JOHN O. MAGRUDER. 70
